[57] CLAIM

The ornamental design for a pushbutton dispenser cap, as shown and described.

DESCRIPTION

FIG. 1 is a front elevational view of a pushbutton dispenser cap showing my new design;

FIG. 2 is a right side elevational view thereof, the opposite side being a mirror image thereof;

FIG. 3 is a perspective view of the top, front and right side thereof; and,

FIG. 4 is a top plan view thereof.

The container upon which the dispenser cap is mounted is shown in broken lines for illustrative purposes only and forms no part of the claimed design.
